[57] **CLAIM**

The ornamental design for an ink tank for printer, as shown and described.

DESCRIPTION

FIG. 1 is a front elevational view of an ink tank for printer showing our new design;
 FIG. 2 is a rear elevational view thereof;
 FIG. 3 is a top plan view thereof;
 FIG. 4 is a bottom plan view thereof;
 FIG. 5 is a left side elevational view thereof;
 FIG. 6 is a right side elevational view thereof; and,
 FIG. 7 is a perspective view thereof.
